[57] CLAIM

The ornamental design for a shoe upper, as shown and described.

DESCRIPTION

FIG. 1 is a side elevational view of a shoe upper showing my new design;
FIG. 2 is a side elevational view of the other side of the shoe upper shown in FIG. 1;
FIG. 3 is a front elevational view of the shoe upper shown in FIG. 1;
FIG. 4 is a rear elevational view of the shoe upper shown in FIG. 1;
FIG. 5 is a top plan view of the shoe upper shown in FIG. 1;
FIG. 6 is a side elevational view of a shoe upper showing another embodiment of my new design;
FIG. 7 is a side elevational view of the other side of the shoe upper shown in FIG. 6;
FIG. 8 is a front elevational view of the shoe upper shown in FIG. 6;
FIG. 9 is a rear elevational view of the shoe upper shown in FIG. 6; and
FIG. 10 is a top plan view of the shoe upper shown in FIG. 6.
The broken line showing of a shoe sole, including the cuffed vertical sides of the sole, is for illustrative purposes and forms no part of the claimed design.
